US00D987472S

(12) **United States Design Patent** (10) **Patent No.:** **US D987,472 S**
(45) **Date of Patent:** **** May 30, 2023**

(54) **BAND ATTACHMENT**

- (71) Applicant: **Apple Inc.**, Cupertino, CA (US)
- (72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Marc A. Newson**, London (GB); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)

- (73) Assignee: **Apple Inc.**, Cupertino, CA (US)

- (**) Term: **15 Years**

- (21) Appl. No.: **29/805,813**

- (22) Filed: **Aug. 30, 2021**

Related U.S. Application Data

- (63) Continuation of application No. 29/702,659, filed on Aug. 21, 2019, now Pat. No. Des. 929,253, which is a continuation of application No. 29/674,905, filed on Dec. 27, 2018, now Pat. No. Des. 857,546, which is

a continuation of application No. 29/573,555, filed on Aug. 8, 2016, now Pat. No. Des. 837,088, which is a continuation of application No. 29/522,353, filed on Mar. 30, 2015, now Pat. No. Des. 763,726, which is a continuation of application No. 29/499,067, filed on Aug. 11, 2014, now Pat. No. Des. 748,527, said application No. 29/573,555 is a continuation of application No. 29/519,909, filed on Mar. 9, 2015, now Pat. No. Des. 763,125, which is a continuation of application No. 29/499,067, filed on Aug. 11, 2014, now Pat. No. Des. 748,527, said application No. 29/573,555 is a continuation of application No. 29/518,898, filed on Feb. 27, 2015, now Pat. No. Des. 764,964, which is a continuation of application No. 29/499,067, filed on Aug. 11, 2014, now Pat. No. Des. 748,527, said application No. 29/573,555 is a continuation of application No. 29/519,117, filed on Mar. 2, 2015, now Pat. No. Des. 763,725, which is a continuation of application No. 29/499,067, filed on Aug. 11, 2014, now Pat. No. Des. 748,527, application No. 29/805,813 is a continuation of application No. 29/702,659, filed on Aug. 21, 2019, now Pat. No. Des. 929,253, which is a continuation of application No. 29/674,905, filed on Dec. 27, 2018, now Pat. No. Des. 857,546, which is a continuation of application No. 29/573,557, filed on Aug. 8, 2016, now Pat. No. Des. 837,089, which is a continuation of application No. 29/522,353, filed on Mar. 30, 2015, now Pat. No. Des. 763,726, which is a continuation of application No. 29/499,067, filed on Aug. 11, 2014, now Pat. No. Des. 748,527, said application No. 29/573,557 is a continuation of application No. 29/519,909, filed on Mar. 9, 2015, now Pat. No. Des.

(57) **CLAIM**

The ornamental design for a band attachment, as shown and described.

DESCRIPTION

FIG. 1 is a bottom front perspective view of a band attachment showing the claimed design;

FIG. 2 is a top rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the band attachment that form no part of the claimed design.
